[57] ABSTRACT

Thread or yarn extending through a pair of thread guides is automatically released and subsequently automatically slidably clamped against the mouth of a passage through one of such thread guides, which mouth is adjacent to the other thread guide. The two thread guides are normally urged toward each other by a spring to maintain the clamping element in its thread-clamping position. The spring force may be overcome by positive mechanical, hydraulic, or pneumatic displacing devices to create a pressure differential to override the spring force and effect thread-releasing relative displacement of the thread guides. The clamping element may be fixed to one of the thread guides, or it may be a free ball movable into and out of thread-clamping position by gravitational force, by wedging action of cooperating inclined surfaces, or by an air stream as the thread guides are moved toward and away from each other, respectively. The thread guides are mounted for conjoint rotation to create rotation of the clamped thread and thereby impart twist to the thread.

SHEET 2 OF 3

ROTATABLE SLIDING-THREAD CLAMP FOR TEXTILE MACHINES¹

Previous thread clamps used, for example, in connection with electrostatic open-end spinning devices have used a ball to clamp and guide thread between the openings of a pair of resiliently-connected adjacent thread guides in cooperation with a thread take-off device which continually draws the thread past the clamps. However, if, for example, the supply of fiber to the spinning device is interrupted to cause a discontinuity in the thread so that the thread end is drawn past the clamp, it has been difficult to rethread the guide means and rethreading usually requires the use of tools such as grippers or hooks.

One solution to this problem was disclosed for use with circular knitting machines in U.S. Pat. No. 3,228,213, in which a spherical clamping unit is moved from clamping engagement with a spun thread by a continuous air stream. This device has limited application, however, because the adjacent pair of thread guides must be fixed and disposed vertically, since gravitational force is the only means for holding the ball or sphere in its clamping position.

It is therefore a principal object of the present invention to provide a simple thread-guiding clamp which can be opened and closed automatically without regard to the stage of textile processing.

A further object is to provide such a thread-guiding clamp arrangement which can be opened or closed during operation of cooperating machinery, such as a spinning machine, so that thread can be supplied to the clamp at any time.

An additional important object is to provide such a clamp which will automatically clampingly engage thread fed to the thread guides when such guides are moved relatively toward each other.

Another object is to provide a clamp which will not damage a thread end during the opening and closing operation.

The foregoing objects are accomplished by having a pair of relatively movable thread guides which are normally resiliently urged toward each other and mounted in a further guide for movement of the thread guides away from each other, and by providing a clamping element located between the thread guides adjacent to the mouths of passages through such guides, which element is movable into its clamping position when the thread guides are moved toward each other. A thread can therefore be fed to the thread clamp while the two thread guides are separated from each other and the clamping element is thereby disposed in a position away from the thread guide mouth against which it clamps. The clamping function is automatically resumed when the thread guides are moved toward each other because such movement urges the clamping element back into its clamping position.

The actuating means for effecting relative movement of the thread guides may be mechanical, electromagnetic or hydraulic, but the preferred construction utilizes a pneumatic system. If hydraulic or pneumatic guide means are used, movement of the thread guides can be effected by providing cooperating fluid passages adjacent to the thread guides into which fluid may be supplied or from which fluid may be evacuated to create a pressure differential sufficient to override the re-

silent force to separate the thread guides and move the clamping element away from its clamping position.

The clamping element may be rigidly connected to one of the thread guides, but is preferably a free sphere movable by rolling along cooperating surfaces of the adjacent thread guide ends to minimize damage to a thread end, particularly during the reclamping operation. By mounting the two thread guides for conjoint rotation, the present invention may be substituted for the twist or lay chamber in pneumatic spinning devices. For this purpose the construction of the thread guide passage are modified in configuration as described more fully below. The clamping arrangement of the present invention can be substituted for the clamping mechanism shown in U.S. Pat. No. 3,492,804, in connection with open-end spinning machines, with the thread guides being moved away from each other in response to a thread-sensing device such as a photoelectric cell.

FIG. 1 is a longitudinal section through one form of thread-clamping device according to the present invention.

FIG. 2 is a longitudinal section through a modified thread-clamping device.

FIG. 3 is a longitudinal section through a thread-clamping device similar to the type shown in FIG. 2 for use in connection with an electrostatic open-end spinning device.

FIG. 4 is a longitudinal section through an open-end spinning device in which the thread clamp of the present invention forms a twist chamber.

In all applications of the present invention, as described below, the thread guide clamp is used in connection with the creation of a genuine or false twist in a thread 1 as the thread is glidingly drawn through the thread clamp. In FIG. 1 the thread glide clamp is shown as including two coaxially arranged generally cylindrical thread guides 2 and 3 having cylindrical, aligned passages therethrough to receive the thread 1. The thread guides are normally urged toward each other by resilient means which may be in the form of a compression spring 4. Thread guide 2 is carried by a holder 42 connected to one end of the armature 40 of an electromagnet 41. Thread guide 3 is carried by a holder 30 which is connected to the carriage of a textile machine (not shown), such as a spinning machine. The thread guides 2 and 3 are rotatively mounted in their respective holders 42 and 30 by ball bearings 43 and 31, respectively, so that the thread guides may turn freely relative to the holders. The thread guides 2 and 3 are rotated synchronously by a common drive shaft 20 carrying respective drive pulleys 21 and 32 connected to the thread guides by drive belts 22 and 33, respectively.

A teardrop-shaped element 23 connected by a bow 24 to the thread guide 2 normally engages the adjacent mouth of the passage through thread guide 3, and thereby constitutes an element of the thread clamp. In FIG. 1 the thread glide clamp is shown in its closed position, whereby thread 1 is clamped between the clamping element 23 and the thread guide 3. Consequently, the thread is rotated by rotation of the thread guides 2 and 3. The compression spring 4 is selected and mounted to exert sufficient pressure to maintain clamping engagement of element 23 and guide 3 with the thread 1 while permitting the thread to be drawn through the clamp. To prevent damage to thread 1 as it is drawn through the glide clamp, element 23 and the

portion of the thread guide 3 which it engages are smooth and rounded so that the thread can glide through the clamp without snagging or abrasion.

To release thread 1 from the clamp, or to open the clamp for feeding a thread into the thread guide passages, an electromagnet 41 is actuated by means not shown, such as a pressure switch, to raise armature 40 in opposition to the force of spring 4 and move thread guide 2 axially away from thread guide 3. The clamp element 23 is thereby moved by bow 24 from engagement with the passage mouth of thread guide 3. In such open position a thread 1 can be dropped or fed easily through the passage of thread guide 2 past the clamp element 23 and through the passage of thread guide 3. The electromagnet 41 is then deenergized so that armature 40 is released, and spring 4 urges thread guide 2 toward thread guide 3 so that the clamp element 23 is automatically returned to the clamping position shown in FIG. 1.

With the construction shown in FIG. 1 there is a possibility that the end of a thread may strike bow 24 as it is fed through the thread guide passages and be damaged thereby. In open-end spinning machines such a damaged thread end may cause difficulty in restarting the spinning operation. Consequently, the modifications shown in FIGS. 2 through 4 use a ball in place of the teardrop 23 and bow 24, which ball is freely movable within the hollow defined between adjacent ends of the thread guides 2 and 3.

The thread clamp of the present invention can be disposed in various positions, and FIG. 2 illustrates horizontally disposed thread guide passages in which a ball 5 is caged by the adjacent ends of thread guides 25 and 35. Such ball 5 is substituted for the clamp construction 23, 24 shown in FIG. 1 and is unattached to any other object. In the exemplary form of the invention shown in FIG. 2, a fan or venting device 51 is operable to partially evacuate a chamber 50 encircling sleeve 6 and thereby to create a pneumatic pressure drop below atmospheric pressure. Sleeve 6 is connected to thread guide 35 to prevent their relative rotation, but the sleeve and guide are rotatable conjointly. Sleeve 6 is mounted in holder 30 by ball bearing 31 and is rotated by belt 22 connected to a drive shaft (not shown).

An axially movable thread guide 25 having an external shoulder 26 is received in a cavity within sleeve 6 inwardly of thread guide 35. Such sleeve has an internal shoulder 60 spaced from and facing the thread guide shoulder 26. A compression spring 61 encircles the smaller portion of thread guide 25 and its opposite ends bear against shoulders 26 and 60, respectively, to normally urge thread guide 25 toward thread guide 35. The thread guide 25 has splined-shaft connections 27, 62 and 28, 63 with sleeve 6. Consequently, thread guide 25 is driven through such connections by sleeve 6 and is thereby turned at the same rotation speed as thread guide 35. The adjacent flared mouths of the passages through the thread guides are countersunk to form oppositely facing frustoconical depressions, each having a depth no greater than the radius of the ball 5, which depressions cooperatively form a cage for the ball.

The annular chamber 50 formed by a channel 53 encircling the sleeve 6 communicates through bores 64 with an internal chamber 52 between sleeve 6 and thread guide 25, in which chamber spring 61 is located. The chamber 50 is connected by a conduit 54 with a

valve 55 movable between two positions. In the full-line position of FIG. 2 the valve 55 provides a passage between conduit 54 and conduit 56 connected to the venting device 51. In its broken-line position the valve 55 passage vents chamber 50 to the atmosphere.

When the device of FIG. 2 is in normal clamping position, chamber 50 and therefore chamber 52 are connected through valve 55 to atmosphere. Consequently, the pneumatic pressure on shoulder 26 from chamber 52 is atmospheric pressure, as is the pressure on the face of thread guide 25 opposite shoulder 26, which face forms the frustoconical depression 29. Spring 61 urges guide 25 toward guide 35 and the cooperating inclined portions of frustoconical depressions 29 and 36 10 slide ball 5 upward to close the adjacent mouths of the cylindrical passages through guides 25 and 35, thereby clamping a thread extending through such passages. As sleeve 6 and guides 25 and 35 are rotated by belt 22, a twist will be imparted to the thread. To open the 15 thread glide clamp for releasing the thread, valve 55 is moved to its full-line position. The chamber 50 and groove 52 are then partially evacuated by the suction fan 51 so that the differential pressure between the atmospheric pressure on the face 29 of thread guide 25 and the reduced air pressure on shoulder 26 overrides the force of spring 61 pressing on such shoulder to move guide 25 away from guide 35. Therefore ball 5 is relieved from pressure by wedging surfaces 29 and 36 and by gravitational force is moved out of the thread 20 path into the position shown in FIG. 2. A thread can therefore be fed through the thread guide passages without interference by the clamping ball.

If desired a liquid rather than air or some other gas, can be used in the pressure-reducing system 52, 50, 54, 35 55, 56, 51, if adequate seals are provided between sleeve 6 and thread guide 25 at opposite ends of chamber 52. In such case the exhaust fan 51 is replaced by a pump, and the valve 55 in its broken-line position communicates with a container for liquid. When the 40 valve is in its full-line position the pump can pump off the liquid in the chambers 52, 50 and recirculate it to the container. The pump can be connected to be energized or deenergized simultaneously with displacement of valve 55.

In order that the longitudinal movement of the thread 45 guide 25 is confined within the sleeve 6, such sleeve is of a length to extend beyond the end of guide 25 remote from guide 35, and the sleeve bore receiving 50 guide 25 is sufficiently longer than such guide to permit movement of the guide within the sleeve between its thread-clamping and thread-releasing positions. In this instance the thread guide passage includes the bore 65 in sleeve 6 coaxial with the passage through guide 25. To facilitate feeding a thread along the entire length of the passage the outer end 66 of bore 65 may be frustoconically countersunk. In addition, a frustoconical depression 29' may be provided in the end of guide 25 adjacent to bore 65. Consequently, feeding a thread 55 through the bore 65 and guides 25 and 35 from right to left as seen in FIG. 2 is facilitated. To similarly facilitate feeding a thread through the device in the opposite direction, additional frustoconical depressions can be provided in the outer end 66' of guide 35 and in the inner end 66' of bore 65.

Forms of the present invention particularly suitable for use with open-end spinning devices are shown in FIGS. 3 and 4. A ball 5 freely movable within the hol-

low between the thread guides is also utilized in these forms of invention as the clamping element. If the thread passage is arranged vertically instead of horizontally, the ball 5 could be moved out of clamping engagement when the thread guides are moved apart relatively by a stream of air created by a pressure differential. Such a device is shown in FIG. 3 in connection with an electrostatic open-end spinning machine including a pair of supply rollers 7, at least one of which is negatively charged, and a positively charged fiber-collecting surface 70 on the outer end of the passage through thread guide 71. The electrostatic field formed between supply rollers 7 and thread guide 71 resolves sliver 11 into individual fibers 10, which fibers are collected on the surface 70 and picked up by the rotating end of a thread 1. Rotation is imparted to the thread by the thread glide clamp mounted by bearings 31 in a holder 30.

The thread guide 71 is rigidly connected to a sleeve 72 for conjoint rotation by a drive belt 22. Sleeve 72 has an internal annular rib 73 on which one end of the compression spring 61 bears. The other end of this spring bears against a nut 74 threaded onto the reduced portion of a second thread guide 75 which the spring encircles. Such nut is held in place by a lock nut 76. Annular rib 73 is located a short distance above the shoulder of guide 75 formed by reducing the upper end portion of such guide and is preferably undercut on its lower side adjacent to such shoulder. The shoulder is chamfered so that the shoulder and undercut rib cooperate to form an annular groove 52 of dovetail cross section. Thread guide 75 has a spline-shaft connection 77, 78 with sleeve 72 to prevent relative rotational movement of guide 75 and sleeve 72 while permitting relative axial movement.

A second sleeve 67 is connected with sleeve 72 by bolts extending through external annular flanges on the adjacent sleeve ends. One end of sleeve 67 receives the lower body portion of thread guide 75 and includes internal grooves 79 of the spline-shaft connection to thread guide 75. The opposite end of sleeve portion 67 is closed by an integral plug 68 having a bore 69 therethrough for passage of thread 1.

The lock nut 76, which cannot turn relative to thread guide 75, has an axial flange 57 spaced from and encircling the reduced end portion of the thread guide 71. Flange 57 has a radial port 58 through it, the lower tangent of which is diametrically aligned with the clamping surface of guide 75. Because guide 75 and sleeve 72 are not rotatable relatively, a bore 59 communicating with chamber 50 is provided through the side of sleeve 72 corresponding to the side of flange 57 having port 58.

In this instance the thread guide 75 is moved axially relative to sleeve 72 and thread guide 71 by creation of a fluid pressure differential in the chamber 52 between the thread guide 75 and the interior of sleeve 72 and atmospheric pressure. However, instead of evacuating the chamber 52 the air pressure in such chamber is increased by supplying air under pressure through conduit 54 to chamber 50 and from such chamber through a plurality of bores or an annular slot 64 through sleeve 72 to chamber 52. Such high pressure air presses downward on the chamfered body shoulder of guide 75 to override the force of spring 61 and thereby moves such guide 75 downward away from guide 71. During such downward movement the bore 58 in extension 57 is

momentarily aligned with bore 59 in sleeve 72 so that a stream of air from chamber 50 impinges on ball 5 and thereby urges it from its centered clamping position toward the left wall of flange 57 as seen in FIG. 3.

With such an arrangement, using the ball-moving air stream, it is necessary to interrupt such air stream before introducing a thread to the guide passage, to prevent feathering or other damage to the thread end or interfering with feeding the thread past such air stream into the next thread guide passage. This is accomplished by further movement of guide 75 away from guide 71. After introduction of the thread 1, the supply of the air to chamber 52 is interrupted so that thread guide 75 is again moved toward clamping position by spring 61. Consequently, there will be no air stream acting on ball 5 when the bores 58 and 59 are again moved in alignment. Thus by continuation of movement of guide 75 toward guide 71, ball 5 is positively wedged into clamping position by the inclined surface of frustoconically flared adjacent end 29 of guide 71.

Pneumatic displacement of ball 5 could be utilized in other forms of thread guide clamps according to the present invention in which the thread guide passages are disposed substantially vertically. For example, suction could be created to move the ball if space 50 were being evacuated when bores 58 and 59 are aligned. Thus it is immaterial whether the pressure differential is created by evacuating chambers 50 and 52 or by supplying air under pressure to such chambers.

Instead of using an air stream to move ball 5 in a vertically disposed thread guide, the adjacent ends of the thread guides may be constructed to cooperate for guiding the ball. Such a construction is shown in FIG. 4.

4. A lower thread guide 8 is enclosed in a vertically disposed sleeve 80 so that such guide and sleeve are not rotatable relatively. The upper surface 81 of guide 8 through which the mouth of the thread passage opens is inclined while the adjacent end surface of thread guide 82, threaded into or bolted to sleeve 80, is conically countersunk to form a depression 83. The axis 84 of such conical depression is disposed perpendicular to the inclined plane of surface 81 of guide 8. When the thread guide clamp is electromagnetically, hydraulically or pneumatically opened in a manner previously described, ball 5 under gravitational force will roll down the incline 81 toward the left, as seen in FIG. 4, until it engages the inner wall of sleeve 80. When the clamp is subsequently closed, the ball 5 will be rolled back up the incline 81 to the thread passage mouth by the wedging action of the conical depression 83 as the thread guide 8 approaches guide 82.

If a thread glide clamp is used in connection with an open-end spinning device which is actuated by a thread-sensing device, such a clamp according to the present invention makes it possible to restart the spinning process automatically because the thread 1 is prevented from being drawn out of the spinning device.

One particularly effective type of thread-sensing device and its responsive actuating system is shown in FIG. 4. The thread sensor includes a light source 44 and a cooperating photoelectric cell 45 which is connected through an amplifier 46 with a relay 47 to operate switch blade 48. Such blade in the full-line position shown in FIG. 4 connects the current supply line to drive motor 49. In the broken-line position of the blade impeller 51 is energized. So long as a thread 1 inter-

rupts the light beam between light source 44 and cell 45, switch blade 48 is maintained in its full-line position to energize motor 49 to drive shaft 20 and belt 22, thereby rotating the thread-clamping device. If the end of thread 1 is drawn past light source 44 so that cell 45 is energized, relay 47 is actuated to swing switch blade 48 into its broken-line position to energize impeller 51 and open the thread clamp so a thread end can be dropped through the thread passage to the spinning device.

The present invention can be used with various types of open-end spinning devices such as pneumatically-operated spinning rotors, rotating or fixed spinning funnels, or spinning chambers in which individual fibers are advanced through a medium to a freely-rotating thread end.

FIG. 4 shows a thread glide clamp of the present invention in connection with a spinning chamber 9 in which fibers 10 attach to the end of thread 1 as such thread is drawn through the clamp by take-off rollers 12. Sliver 11 is fed by rollers 7 to a horizontal feed tube 90 which supplies fibers 10 from such sliver into the side of the spinning chamber 9 in a conventional manner. The take-off tube 91 connected to the upper side of the spinning chamber is made of transparent material or includes a window between light source 44 and cell 45 located on opposite sides thereof. The thread glide clamp is located above the take-off tube 91 in place of a conventional twist-forming chamber in a position having sleeve 80 and thread guides 8 and 82 in axial alignment with tube 91. Sleeve 80 is mounted by ball bearings 31 on the housing 92 for the spinning chamber 9, which housing is connected to a suction conduit 93 below the spinning chamber. Similar to FIG. 3, sleeve 80 has an internal annular rib 73. Thread guide 8 has a skirt 85 below such rib, and the upper shoulder formed by the skirt is chamfered and cooperates with rib 73 to define a chamber 52 of dovetail cross section. Splined-shaft connections 77, 87 and 86, 79 between sleeve 80 and skirt 85 effect conjoint rotation of these components.

To improve the distribution of twist using the glide clamp of the present invention with an open-end spinning device, the thread passages through guides 8 and 82 are modified in configuration. While the major length of the passage 96 through guide 8 and skirt 85 is concentric with the axis of sleeve 80, the mouth 94 of such passage adjacent to ball 5 is offset from such axis to form a passage portion having an axis diverging at an acute angle from the vertical axis of sleeve 80. Similarly, the mouth 97 of the passage of guide 82 remote from ball 5 is concentric with the sleeve axis, but mouth 95 adjacent to ball 5 is offset from such axis, the mouths 94 and 95 being in alignment with each other.

The sliding-thread clamps shown in FIGS. 3 and 4 impart a genuine twist to the thread 1. If the thread clamp is used by placing it between a spinning turbine (not shown) and a pair of take-off rollers, the clamp will create a false twist which facilitates combination of individual fibers to form a thread. The sliding-thread clamp can also be used to advantage in connection with false twist spinning machines or other textile machines.

We claim:

1. A rotatable sliding-thread clamp including two coaxially aligned thread guides each having a thread-receiving passage therethrough, such passages forming

mouths at their openings through the thread guide ends, the adjacent thread guide ends defining a hollow therebetween, resilient means normally urging such thread guides axially toward each other, and a clamping element disposed in the hollow between such thread guide ends, the improvement comprising first control means for relatively moving such thread guides axially away from each other against the force of such resilient means, and second control means for positively moving the clamping element between a clamping position and a position in which the thread passages through both of said thread guides are unobstructed by said clamping element in coordination with the movement of the thread guides toward and away from each other, respectively.

2. The clamp defined in claim 1, in which the second control means includes a link connecting the clamping element to one of the thread guides for conjoint relative movement therewith.

3. The clamp defined in claim 1, in which the thread-receiving passages through the thread guides are disposed substantially vertically, the clamping element is a ball, the first control means including means for creating a pressure differential between the hollow defined by the adjacent ends of the thread guides and a fluid receiving chamber connected to a portion of one of the thread guides remote from the hollow, and the second control means including means for momentarily connecting said chamber with the hollow to provide a fluid stream impingeable on said ball.

4. The clamp defined in claim 1, in which the thread guides are disposed one above the other, and the thread-receiving passages are disposed substantially vertically, the lower thread guide having an upper inclined surface through which a mouth of the thread-receiving passage through such guide opens, and the upper thread guide having a lower surface through which a mouth of the thread-receiving passage through such guide opens, having a conical depression, the axis of said depression being perpendicular to said inclined surface of the lower thread guide.

5. The clamp defined in claim 1, in which the thread-receiving passage through each thread guide includes a first passage portion remote from the clamping element extending axially of its thread guide and a second passage portion having its axis inclined at an acute angle to the axis of its thread guide, the mouths of the inclined passage portions opening into the hollow between the thread guides and being offset from their respective thread guide axes and being in substantial alignment.

6. The clamp defined in claim 1, the first control means including pneumatic means for effecting relative axial movement of the thread guides away from each other against the force of the resilient means.

7. The clamp defined in claim 1, further comprising a sleeve, mounting means rigidly connecting one thread guide in said sleeve, means connecting the other thread guide with said sleeve for axial movement relative to said sleeve and said one thread guide and for conjoint rotation with said one thread guide and said sleeve, a first fluid-receiving chamber externally of the sleeve, a second fluid-receiving chamber between one thread guide means and the sleeve, means connecting said first and second fluid-receiving chambers, and means for altering the pressure of fluid in said chambers.
